US0D1076592S

(12) **United States Design Patent** (10) **Patent No.:** **US D1,076,592 S**
(45) **Date of Patent:** **** May 27, 2025**

(54) **LID**

(71) Applicant: **YETI Coolers, LLC**, Austin, TX (US)

(72) Inventors: **Dustin Bullock**, Austin, TX (US);
Colin Darling, Austin, TX (US); **Evan Goldberg**, Austin, TX (US)

(73) Assignee: **YETI Coolers, LLC**, Austin, TX (US)

(**) Term: **15 Years**

(21) Appl. No.: **29/917,694**

(22) Filed: **Nov. 21, 2023**

(56)

(57) **CLAIM**

The ornamental design for a lid as shown and described.

DESCRIPTION

FIG. 1 is a front, right isometric view for a lid showing our new design;

FIG. 2 is front view thereof;

FIG. 3 is a rear view thereof;

FIG. 4 is a right view thereof;

FIG. 5 is a left view thereof;

FIG. 6 is a top view thereof; and,

FIG. 7 is a bottom view thereof.

The broken lines form no part of the claimed design.

1 Claim, 4 Drawing Sheets

See application file for complete search history.
